UNITED STATES PATENT OFFICE

152,206

DESIGN FOR A TIP FOR A MECHANICAL PENCIL

Lucifer J. Most, Dover, N. J.

Application September 12, 1947, Serial No. 141,351

Term of patent 14 years

(Cl. D74—1)

To all whom it may concern:

Be it known that I, Lucifer J. Most, a citizen of the United States, residing at Dover, in Morris County, State of New Jersey, have invented a new, original, and ornamental Design for a Tip for a Mechanical Pencil, of which the following is a specification, reference being had to the accompanying drawing, forming part thereof.

Figure 1 is an elevation of the tip for a mechanical pencil, showing my new design.

Figure 2 is an elevation taken at right angles to that of Figure 1.

Figure 3 is a top plan of the tip.

I claim:

The ornamental design for a tip for a mechanical pencil, as shown.

LUCIFER J. MOST.
